UNITED STATES PATENT OFFICE

2,436,006

OVERHEAD DOOR

Frederick Kaiser, Elkins Park, Pa., assignor to
Better-Bilt Door Company, Egg Harbor, N. J.,
a corporation of New Jersey

Application January 18, 1945, Serial No. 573,385

5 Claims. (Cl. 160—191)

1 The instant invention relates to doors and more particularly to a door of the overhead type.

One of the primary objects of the invention is the construction of a door of the character indicated having a plurality of hinged panels, guiding tracks and door counterbalancing means, the tracks and counterbalancing means being so arranged relative to each other and the door opening as to occupy a minimum of space both vertically and laterally.

Still a further aim is to make a door of the type specified which will be of sturdy construction and embody simple and novel means for both positioning the counterbalancing means in an optimum position with respect to the door panels and for attaching said means to the latter.

The above and other aims and objects will be apparent from the detailed description hereinafter appearing when taken in conjunction with the appended drawings to which reference is now made and in which

Figure 1 is a perspective view showing a portion of a door of the overhead type in down or closed position in a door opening together with the door counterbalancing means, all as viewed from one side thereof;

Figure 2 is an enlarged sectional view taken on line 2—2 of Figure 1;

Figure 3 is an enlarged rear elevational view of the door panels and operating chain;

Figure 4 is an enlarged front elevational view showing bracket means for attaching the chain of the counterbalancing mechanism to a corner of the door panels;

Figure 5 is a side elevational view, partly in section, of the attaching means of Figure 4; and

Figure 6 is an enlarged sectional view taken on line 6—6 of Figure 1.

Referring to the drawings, it will be seen that the reference character D designates a garage door or the like operatively positioned in a door opening, said door being composed of a plurality of hinged panels P, three panels being shown connected to each other at their adjacent longitudinal edges by means of hinges 10 mounted on the rear side 11 of the door D. It will be understood that the structure shown in the various figures of the drawings is duplicated on the left hand side of the door, Figure 1 showing the right hand side. A vertically extending channelled track 12 is positioned within the door opening in spaced relation to the vertical edges 13 of the panels P. The reference numeral 14 designates an upper horizontal track secured to the wooden ceiling jamb 15 by means of spaced U-

2 shaped bracket 16, see Figures 1 and 6. A second horizontal track 17 is positioned below and in abutting relationship to and in vertical alignment with track 14, said tracks being rigidly welded or otherwise secured to each other. Arcuate track portion 18 connects vertical track 12 with horizontal track 17.

Each hinge 10 includes a pintle 10^a having a roller 10^b journaled thereon. As will be seen in Figure 1, the uppermost roller 10^b rides on upper horizontal track 14 while the other rollers ride on vertical track 12, arcuate track portion 18 and horizontal track 17.

The counterbalancing means C for the door D comprises a chain 20, sheaves 21 and 22 and a coil spring 23. As will be seen in Figure 1, one end 24 of spring 23 is secured to a vertically disposed angle bracket 25 as at 26, the other end of the spring terminating in a U-shaped journal

20 member 27 rotatably mounting sheave 22 on a shaft fixed in said journal member. A depending fixed support 29 rotatably supports sheave 21 and it will be seen that the counterbalancing means C is in its entirety located below and in vertical alignment with the horizontal tracks 14 and 17. One end of chain 20 is secured to support 29 as at 30 by means of a hook 31 or the like, the chain then passing over sheaves 22 and 21, the other end of the chain being secured to the lower corner of the lowermost panel P of the door D in a manner now to be described.

A plate bracket member 40 is fixed to a corner of the lowermost panel P of the door D on the rear face 11 of said panel by means of screws or the like.

Said corner bracket member 40 comprises a flat portion 41, a pair of spaced outwardly projecting ears 42 and 43 in which is fixed the shaft 10^c, the latter rotatably journaling a roller 10^d. Lowermost end of chain 20 is fastened by means

40 of a clip 44 and cotter pin 45 or the like to ear 43. By an inspection of Figures 1 and 3, it will be noted that chain 20 is at all times either in alignment with or inwardly of the tracks 12, 14 and 17. Consequently, by having the counter-

45 balancing mechanism C, in either the open or closed position of the door D, below and in alignment with tracks 14 and 17 with the chain 20 of the mechanism arranged and fastened as indicated above, a minimum of space is required for the door operating means within the door opening resulting in a maximum saving of both headroom and sideroom. Thus, one of the primary objects of the instant invention is attained.

While the invention has been described in detail, it will be apparent to those skilled in the art

that various changes may be made in the specific construction shown. It is desired to cover all such changes and to be limited in this respect only as may be necessary by the scope of the claims hereto appended.

What I claim and desire to secure by Letters Patent is:

1. An overhead door construction comprising a door having a plurality of panels hingedly connected to each other and adapted to close a door opening, a pair of horizontal tracks extending rearwardly from the top of said opening, said tracks being rigidly connected to each other and positioned one above the other in the same vertical plane, a vertical track spaced from the vertical edges of said panels and connected to the lowermost of said horizontal tracks, a counterbalancing mechanism connected to said door and positioned below and in vertical alignment with said horizontal tracks, said door panels having rollers riding in said tracks.

2. An overhead door construction comprising a door having a plurality of panels hingedly connected to each other and adapted to close a door opening, a pair of horizontal tracks extending rearwardly from the top of said opening, said tracks being rigidly connected to each other and positioned one above the other in the same vertical plane, a vertical track spaced from the vertical edges of said panels and connected to the lowermost of said horizontal tracks, a counterbalancing mechanism connected to said door and positioned below and in vertical alignment with said horizontal tracks, said counterbalancing mechanism comprising sheaves, a spring and a chain connected to the lowermost of said door panels inwardly of said vertical track, and said door panels having rollers riding in said tracks.

3. An overhead door construction comprising a door having a plurality of panels hingedly connected to each other and adapted to close a door opening, a pair of horizontal tracks extending rearwardly from the top of said opening, said tracks being rigidly connected to each other and positioned one above the other in the same vertical plane, a vertical track spaced from the vertical edges of said panels and connected to the lowermost of said horizontal tracks, a counterbalancing mechanism connected to said door and positioned below and in vertical alignment with said horizontal tracks, said counterbalancing mechanism comprising sheaves, one of said sheaves being supported by a fixed bracket and the other supported by a movable journal, a spring connected to said journal and a chain having one end connected to said bracket and riding over said sheaves, the other end of said chain being connected to a corner of the lowermost of said door panels inwardly of said vertical track, and said door panels having rollers riding in said tracks.

4. An overhead door construction comprising a door having a plurality of panels hingedly connected to each other and adapted to close a door opening, a pair of horizontal tracks extending rearwardly from the top of said opening, said tracks being rigidly connected to each other and positioned one above the other in the same vertical plane, a vertical track spaced from the vertical edges of said panels and connected to the lowermost of said horizontal tracks, a counterbalancing mechanism connected to said door and positioned below and in vertical alignment with said horizontal tracks, said counterbalancing mechanism comprising sheaves, one of said sheaves being supported by a fixed bracket and the other supported by a movable journal, a spring connected to said journal and a chain having one end connected to said bracket and riding over said sheaves, a plate secured to the corner of the lowermost of said door panels, said chain having one end connected to said plate inwardly of said vertical track, and said door panels having rollers riding in said tracks.

5. An overhead door construction comprising a door having a plurality of panels hingedly connected to each other and adapted to close a door opening, a pair of horizontal tracks extending rearwardly from the top of said opening, said tracks being rigidly connected to each other and positioned one above the other in the same vertical plane, a vertical track spaced from the vertical edges of said panels and connected to the lowermost of said horizontal tracks, a counterbalancing mechanism connected to said door and positioned below and in vertical alignment with said horizontal tracks, said counterbalancing mechanism comprising sheaves, one of said sheaves being supported by a fixed bracket and the other supported by a movable journal, a spring connected to said journal and a chain having one end connected to said bracket and riding over said sheaves, a plate secured to the corner of the lowermost of said door panels, said plate having a pair of spaced outwardly projecting ears, a shaft fixed in said ears, said shaft having a roller rotatably supported at one end thereof and ridable in one of said tracks, one end of said chain being secured to one of said ears inwardly of said vertical track, and said door panels having other rollers riding in said tracks.

FREDERICK KAISER.
